UNITED STATES PATENT OFFICE.

ALBIN STEINER, OSKAR LIEBERMANN, AND CARL SCHARFENBERG, OF SONNEBERG,
GERMANY, ASSIGNORS TO LEON REES, OF LONDON, ENGLAND.

SOUNDING FIGURE TOY.

1,098,303.

Specification of Letters Patent. Patented May 26, 1914.

Application filed December 19, 1913. Serial No. 807,765.

To all whom it may concern:

Be it known that we, ALBIN STEINER, OS-
KAR LIEBERMANN, and CARL SCHARFENBERG,
subjects of the Emperor of Germany, resid-
ing at Sonneberg, Germany, have invented
certain new and useful Improvements in
Sounding Figure Toys, of which the follow-
ing is a specification.

The invention relates to toys in the form
of dolls, puppets, animals or the like with
inflated bladders resembling squeakers.

The special feature of the invention is
that the operating of the reed in imitation
of the squeaker and the working of the air-
bladder which takes the place of the latter
are effected by one and the same mechan-
ical means (a collapsible air-tight bellows or
the like) but by different volumes of air.
The advantage of this arrangement is that
the air bladders which in such toys are easily
damaged can be exchanged, without its be-
ing necessary to renew the reed at the same
time. A toy of this kind can also be em-
ployed without an air-bladder and the reed
notwithstanding be caused to sound.

One form of the invention is illustrated
on the annexed drawings Figure 1 being a
longitudinal section with a person's head ap-
plied; Fig. 2 a section on the line *a b* of
Fig. 1.

In the example illustrated, the appliance
which forms part of a doll consists of an
air tight bellows 1 which can be put under
tension by a spring 2 and is provided with
two end plates 3, 4. Preferably on the lower
plate 4 a reed 5 is arranged which is oper-
ated by the air that enters through a hole 6
in the plate and passes through a non return
valve 7 into the bellows. In the other or
upper plate 3 is a hole 8 with air valve 9.
On the upper plate 3 the head 10 of the doll
or puppet which is made of air-tight ma-
terial is fixed or connected. In the mouth
opening 11 of the head an air bladder 12 is
45 inserted or connected which outwardly has
any preferred form and preferably has no
reed. A small hole 13 in the head allows of
escape of air.

The action of the device is as follows: If
the bellows 1 be compressed, the valve 7 in
the lower plate 4 is closed and the air con-
tained in the bellows 1 is forced through the
opening 8 in the upper plate through the air
valve 9 into the head 10 and thence into the

air-bladder 12 which is thus inflated. When 55
the bellows 1 is released it is expanded by
its spring 2 and the valve 9 in the upper
plate closes, thus shutting off the air con-
tained in the head 10 and in the air bladder
12, but at the same time the reed 5 is caused 60
to sound by the air drawn in from below
through the hole 6 of the lower plate 4 into
the bellows. Now in order that in accord-
ance with the well known natural action of
squeakers the air bladder 12 shall curl up 65
or deflate when the sound of the reed 5 dies
away, the small hole 13 is provided in the
head 10 and through this the air contained
in the bladder can escape, the size of this
air outlet opening being such that the air 70
bladder does not curl up completely before
the reed has ceased sounding.

The air bladders employed may vary in
form and also be arranged in the known
manner to roll up when the air escapes. 75

As will be understood the appliance may
be of varied construction and applied to
puppets, toy animals and the like and in
some cases the head may be connected with
the bellows by a pipe. 80

In making up the doll shown on the draw-
ings the bellows form the body portion and
the arms can be secured to the upper plate
3 while the legs can be secured to the lower
plate 4 and the whole be dressed according 85
to the style required.

What we do claim as our invention and
desire to secure by Letters Patent is:—

1. A sounding figure toy provided with
an inflatable and collapsible part, a main 90
body provided with a sound producing de-
vice and means for supplying separate vol-
umes of air for operating the inflatable and
collapsible part and the sound producing
device. 95

2. A sounding figure toy provided with
an inflatable and collapsible part, a hollow
main body comprising two end plates and
collapsible walls secured thereto, a valve
controlled opening between one of said 100
plates and said inflatable and collapsible
part, a sound producing device provided
in the other end plate, and a spring inter-
posed between said end plates, whereby
when the main body is compressed the in-
flatable and collapsible part will be in- 105
flated and when released the sound produc-
ing device will be operated.

3. A sounding figure toy comprising a hollow main body consisting of two end plates, collapsible walls secured thereto, and a spring interposed between said end plates, 5 a part mounted on one of said end plates and provided with an inflatable and collapsible device, said part having an exterior aperture and a valve controlled opening between said part and said end plate, a sound 10 producing device mounted in the other of said end plates and a valve controlled opening for admitting air to the main body

through said sound producing device, and operating the latter.

In testimony whereof we have hereunto 15 set our hands in presence of two subscribing witnesses.

ALBIN STEINER,
OSKAR LIEBERMANN.
CARL SCHARFENBERG.
